ATTORNEY

UNITED STATES PATENT OFFICE.

HENRY RUPPEL, OF CLEVELAND, OHIO, ASSIGNOR TO THE Dangler STOVE AND MANUFACTURING COMPANY, OF SAME PLACE.

DESIGN FOR A VAPOR-BURNER.

SPECIFICATION forming part of Design No. 28,269, dated February 8, 1898.

Application filed December 31, 1897. Serial No. 665,234. Term of patent 7 years.

To all whom it may concern:

Be it known that I, HENRY RUPPEL, a citizen of the United States, residing at Cleveland, in the county of Cuyahoga and State of Ohio, have invented and produced a new and original Design for Vapor-Burners, of which the following is a specification, reference being had to the accompanying drawings, forming part thereof.

10 Figure 1 is a side elevation of a burner showing my new design. Fig. 2 is a plan view thereof. Fig. 3 is a side elevation viewed from the left of Fig. 1 and at right angles to said figure.

15 As shown in the drawings, the leading or material feature of the design consists in the configuration thereof as viewed in plan and

elevation and comprises a circular base A, an ornamental mounting B thereon, an elbow C, and curved arm D. The said elbow and arm lie wholly outside the contour of the base when viewed in plan, except that the shoulder of the elbow extends inward to a point centrally beneath the base.

What I claim is—

20 The design for a vapor-burner, as herein shown and described.

Witness my hand to the foregoing specification this 30th day of December, 1897.

HENRY RUPPEL.

Witnesses:

H. T. FISHER,
R. B. MOSER.
